UNITED STATES PATENT OFFICE.

EDWARD E. NOLAN, OF GRAND RAPIDS, MICHIGAN.

AERIAL LADDER.

SPECIFICATION forming part of Letters Patent No. 684,520, dated October 15, 1901.

Application filed June 27, 1900. Serial No. 21,839. (No model.)

To all whom it may concern:

Be it known that I, EDWARD E. NOLAN, a citizen of the United States, residing at Grand Rapids, in the county of Kent and State of Michigan, have invented certain new and useful Improvements in Aerial Ladders, of which the following is a specification.

My invention relates to improvements in aerial ladders for use by fire departments for reaching the upper stories in high buildings; and its objects are, first, to provide an aerial ladder that may be continuously extended from a reel with an assurance of ample rigidity; second, to provide for a uniform convenient extension of the ladder, and, third, to provide for quickly and conveniently adjusting said ladder to the place and position desired. I attain these objects by the mechanism illustrated in the accompanying drawings, in which—

Figure 1 is a plan of the ladder and truck with the platform removed to show the relative positions of the several actuating and operative parts. Fig. 2 is a side elevation of the same with the ladder elevated and the platform in place. Fig. 3 is the same dismantled and the ladder down in position for storing to show the appliance for operating the turn-table and raising the ladder from the platform. (Not shown in Figs. 1 and 2.) Fig. 4 shows the turn-table and ladder carried one-fourth around, so that the ladder may be operated from the side of the truck. Fig. 5 is a sectional elevation of the turn-table and body of the truck on the line xx of Fig. 1. Fig. 6 shows the mechanism for regulating the angle of the ladder by hand. Fig. 7 shows the top of the reel-support with the gear-wheel and pawl for elevating the ladder support and holding it to position. Fig. 8 is a side view. Fig. 9 is an end view, and Fig. 10 is a plan of the folding length or extensions of the ladder. Fig. 11 is a sectional view of the ladder and ladder-support on the line xx of Fig. 1. Fig. 12 is a plan of the tongue; and Fig. 13 shows the reel-shaft, &c. Similar letters refer to similar parts throughout the several views.

A represents the front truck, and A' represents the hind truck, that supports my ladder. G' is the frame of the truck, and it has a

backwardly-extending portion B', designed to support the ladder when not in active use, and T is the tongue by which the trucks are drawn. The ladder E is supported in a support or guideway G, that is pivoted to the standards G' in such a manner that the outer end may be carried up toward a vertical position, as shown in Fig. 2. This may be accomplished in one of three ways or in two of the three ways combined. First, it may be elevated by means of the screw-gear P P², actuated by the shaft and hand-wheel P³, as indicated in Fig. 3; second, it may be raised by hand by means of the gear-wheels P and W, actuated by the crank g, and, third, it may be actuated by the gear-wheel I' and the arm I, which is attached at the other end to the side of the guideway G, and may be actuated by means of the crank J² (shown in Fig. 7) or by the bevel-gear j' j, actuated by the hand-wheel and shaft J, and it may be locked to place by the pawl i, engaging the gear-wheel I', as indicated in Fig. 7. The ladder may also be raised, by means of the cable U', in the following manner: The draft of the entire truck is upon the rod U, which is slidingly secured under the tongue T, the back end being attached to the whiffletree T', which in turn is held to place by the pin M'. The front end of the cable U' is attached to the whiffletree T', whence the cable extends back around the idlers u' and u and around the wheel U², which is mounted upon the shaft F², that carries the gear-wheels I'. Wishing to raise the ladder by the horses, the linchpin M' is drawn by means of the cord M, as indicated by the dotted lines in Fig. 2, and the rod U, the whiffletrees T', and the cable U' will be drawn forward, as indicated by the dotted lines in Figs. 1, 2, and 12, which will cause the shaft F², and with it the gear-wheels I', to revolve and draw the arms I forward and the ladder toward a vertical position, as hereinbefore described. The extensions E' of the ladder are stored and supported upon the reel D, which is supported upon the standards F and is arranged to revolve upon the shaft F' by means of the hollow shaft or hub F², to which it is secured, and the whole is supported upon the turn-table C, which is made to revolve freely by means of

- the ball-bearings or antifriction-rollers C', which action may be further facilitated by the use of a broad head X' to the king-bolt X, between which and the top of the turn-table
- 5 I place a series of balls c to form an ordinary ball-bearing. This turn-table may be made to revolve, by means of the gear-wheels o o', through the medium of the hand-wheel and shaft o² in the usual manner of revolving
- 10 heavy turn-tables of this character. The extensions E' are made of a proper length between pivot-points to just fit over each division of the reel D, so that they may be rolled upon the reel or run out from the reel, as desired.
- 15 To insure a rigid joint between these extensions, I form a narrow bearing e upon the ends and corresponding side supports e' upon the body of the extension in position to receive the bearing e of the adjacent extension, the two being wedging and dovetailed, so that they will form a very strong rigid joint when fully interlocked. The adjacent ends are pivoted together by means of the bolt e², passing through one extension, so that it is
- 20 held rigidly to place, and through a slot, as e³, in the other extension, so that it may be made to slide lengthwise sufficiently to properly enter or withdraw the bearing e, as hereinbefore described. The upper length of the ladder E should be considerably longer than the extensions and normally is supported in the guide-frame G, so that it may be carried out longitudinally and will draw the extensions after it until they are far enough advanced to
- 25 be engaged by the elevating device, a very convenient form of which I show at H in Figs. 1, 2, and 11, which is a belt mounted upon and driven by the pulleys L and L' in such a manner that when the pulley L is made to revolve
- 30 either by the crank H² in Fig. 1 or by the bevel gear-wheels H' and hand-wheel and shaft h the projecting arms h will be forced against the lower edge of the ladder-rungs g' and will force the ladder up and out of the
- 35 support. I place an idler l in position to hold the belt H parallel with the ladder from the pulley L to Q, whence it is made to incline away from the ladder until the pulley L' is reached to gradually draw the arms h from
- 40 contact with the rungs g' of the ladder. As it is necessary to carry the extensions up to enter the two parts together before the extension is forced up to form a portion of the ladder, I find it advisable to use an auxiliary elevator, as indicated at L² in Fig. 11, which may
- 45 be so adjusted as to raise the extension or the ladder slightly before the elevator proper comes in contact with the rungs of the ladder to raise it.
- 50 In the application of the hose I prefer that the portion N be made of ordinary iron pipe and that the nozzle n be rigidly attached to it and bent to one side, as indicated, so that an operator may turn the pipe and nozzle to the
- 55 desired direction, as indicated by the dotted lines in Fig. 11, without being to the necessity of standing at the top of the ladder. The

balance of the hose may be stored upon a spool, as N², the hose N' being flexible and wound thereon in the usual manner. This storage-spool may be mounted upon a shaft, as n³, and should be provided with a coiled spring, as n⁴ (see Fig. 5) of sufficient length and strength to rewind the hose as the ladder is being lowered. The reel D may be provided with a coiled spring, as V, for re-coiling the ladder as it is being lowered; but I do not deem it practical to do so for the reasons, first, it would require so strong a spring to take care of the ladder that the strain upon the elevators would be greatly increased; second, it would require so long a spring that it would be next to impossible to give it the necessary strength, and, third, it would render it necessary to greatly increase the weight and strength of the reel to support the added strain of the spring.

For the purpose of bracing the ladder when extended I place a cable S upon a reel R in position so that the cable will pay out as the ladder extends, and a bridge, as indicated at S' in Fig. 2, by means of which the entire strength of the cables may be made available to assist in supporting the ladder and its load. When it is found necessary to throw the ladder around to one side of the truck, as indicated in Fig. 4, and to place it at a low incline, as indicated in Fig. 2, there is great danger of tipping the trucks over. To avert this danger, I place a pair of strong slides Y upon the turn-table C in position so that they may be drawn out to greatly change the supporting-base to meet any desired change in the center of gravity of the ladder and hinge a standard Y' to the outer end thereof, which should extend to the ground, and to further strengthen it a brace Y² may be placed from the top of the standards to the ladder, all as indicated by dotted lines in Fig. 2. The platform K is designed for the operators when manipulating the ladder, and the actuating-shafts and hand-wheels J, o², and p², and h' are all so situated as to be easily accessible therefrom. The ladder K' is fitted with an extension K², that may be thrown down, so that the platform may be easily accessible when the ladder is carried around to one side of the trucks, as in Fig. 4.

I do not desire to restrict my invention to the exact construction herein shown and described, but wish to cover any and all available modifications thereof that may come within the principle of "mechanical equivalents"—as, for instance, there are several forms of connecting appliances that may be made to perform the office of the bearing e and the supports e'—the germ of my invention lying more in the manner of storing and manipulating the ladder than in the individual mechanical appliances by which these objects are attained.

In Fig. 3 I have shown at Z a brake that may be actuated by means of the hand-wheel and shaft Z' and the cord or cable z to secure

the holding of the trucks rigidly to place when manipulating the ladder either by hand or with the horses, as hereinbefore described.

Having thus fully described my invention, 5 what I claim as new, and desire to secure by Letters Patent of the United States, is—

1. In an aerial ladder, a supporting-truck, a turn-table thereon, a reel mounted on said turn-table, a pivoted support also mounted 10 on said turn-table, an extensible ladder on said support and said reel the extensions whereof are adapted to form a rigid ladder when extended, and mechanism for elevating and extending said ladder, substantially as 15 and for the purpose set forth.

2. In an aerial ladder, a supporting-truck, a turn-table mounted thereon ball-bearings supporting it, a reel mounted on said turn-table, an adjustable support pivoted at one 20 end to standards on said turn-table back of the reel a ladder formed of a long upper section and a series of shorter extensions fitted to be stored upon and extended from said reel, arms and gear connected to manipulate 25 the pivoted support, an elevator secured to the support and engaging the rungs of the ladder, and a gear-wheel and crank connected therewith, substantially as and for the purpose set forth.

3. In an aerial ladder, a supporting-truck, a turn-table mounted thereon, a pivotal bolt securing said turn-table to the truck, and having a broad head, ball-bearings between the turn-table and the truck-bottom and between the turn-table and the broad bolt-head, 35 a reel and sectional ladder on said turn-table, and mechanism for operating the ladder, substantially as and for the purpose set forth.

4. In an aerial ladder, a supporting-truck, 40 a turn-table revolvably supported thereon, a reel supported on standards on said turn-table, a support pivoted at one end to standards on the turn-table back of the reel, a hollow shaft for supporting said reel, a solid 45 shaft passing through said hollow shaft and supported on the standards, gear-wheels on the ends of said shaft, arms connecting said gear-wheels with the support, a sheave on one end of said shaft, idlers upon said turn-table, 50 a tongue upon the truck, whiffletrees secured to the tongue, a cable wound on said sheave and extending thence over said idlers to and connected with the whiffletrees under the tongue, a sliding auxiliary tongue or rod attached to the whiffletrees, and a removable 55 linchpin, all so arranged that the drawing of the linchpin will allow the whiffletrees to slide forward, draw the cable, revolve the

shaft and raise the support, substantially as and for the purpose set forth. 60

5. In an aerial ladder, a supporting-truck, a turn-table revolvably mounted on said truck, a reel mounted on said turn-table, a guideway pivoted at one end to standards on said turn-table back of the reel, a ladder supported in said guideway, short extensions back of said ladder and stored on the reel, an elevator on said support in position to engage the rungs of the ladder, a shaft within the reel, gear-wheels on said shaft, arms connected to the support and engaging said gear-wheels, a screw-gear connected with the pivoted end of the support, a gear-wheel and shaft connected with the elevator mechanism, and an auxiliary elevator, substantially 75 as and for the purpose set forth.

6. In combination with the supporting-trucks, turn-table, pivotal support, and extensible ladder, a hose connected to the upper section of ladder, a flexible hose connected therewith and coiled upon a storage-reel, and a storage-reel mounted on the turn-table and having an actuating-spring, and a cable and reel attached to the ladder and support, substantially as and for the purpose set forth. 80

7. In an aerial ladder, a truck, a turn-table upon said truck, a guideway pivoted at one end to the turn-table, elevators upon said guideway, a reel, a sectional extensible ladder upon said reel the ends of the stiles of 90 which are tapered and beveled to form the tongue of a dovetail joint, dovetail sockets on each end of said stiles arranged to interlock with the tongues of the adjacent stiles, and said stiles pivoted together and provided with 95 slots for the longitudinal adjustment of the dovetail joints, substantially as and for the purpose set forth.

8. In combination, a truck, a reel revolvably mounted thereon, a ladder made up of extensions pivotally connected and stored upon said reel, interlocking joints formed upon the connected ends of said extensions, a pipe and nozzle secured to the upper section of said ladder to be readily revolved, a hose attached 100 to the lower end of said pipe, a hose-reel upon the turn-table, a guideway and an elevator attached thereto, substantially as and for the purpose set forth.

Signed at Grand Rapids, Michigan, May 110
26, 1900.

EDWARD E. NOLAN.

In presence of—

I. J. CILLEY,
F. D. DIBBLE.
